UNITED STATES PATENT OFFICE

124,031

DESIGN FOR A SHOWER CABINET

Warner W. Hoople, Evanston, Ill., assignor to Henry Weis Manufacturing Company, Inc.,
Elkhart, Ind.

Application June 5, 1940, Serial No. 92,831

Term of patent 14 years

To all whom it may concern:

Be it known that Warner W. Hoople, a citizen of the United States, residing at Evanston, in the county of Cook and State of Illinois, have invented a new, original, and ornamental Design for a Shower Cabinet, of which the following is a specification, reference being had to the accompanying drawing, forming part thereof.

Fig. 1 is a perspective view of a shower cabinet showing my new design; and

Fig. 2 is an enlarged horizontal sectional view showing in top plan the surface of the receptor portion of the cabinet.

The essential feature of my design resides in the ornamentation on the floor of the receptor portion, best shown in Fig. 2.

I claim:

The ornamental design for a shower cabinet, as shown and described.

WARNER W. HOOPLE.
